UNITED STATES PATENT OFFICE.

CHARLES M. GENTHNER, OF AURORA, ILLINOIS, ASSIGNOR TO RATHBONE, SARD & COMPANY, OF AURORA, ILLINOIS.

DRAFT-REGULATOR FOR STOVE-DOORS.

No. 866,197.

Specification of Letters Patent.

Patented Sept. 17, 1907.

Application filed February 25, 1907. Serial No. 359,072.

To all whom it may concern:

Be it known that I, CHARLES M. GENTHNER, a citizen of the United States, residing at Aurora, in the county of Kane and State of Illinois, have invented certain new and useful Improvements in Draft-Regulators for Stove-Doors, of which the following is a specification.

My invention relates to heaters and has special reference to the draft regulating mechanism in the doors of stoves, ranges and furnaces.

10 The chief objects of my invention are to produce a simple and efficient device for regulating the admission of air to the fire boxes or ash-pits of heating stoves and furnaces; to provide means for producing and maintaining a practically air tight closure between the sliding 15 and fixed members of a stove door; to produce a device for the purpose stated having means for retaining the parts in adjusted positions; and to furnish an operating member for dampers that can be readily actuated by means of either hand or foot, and also adapted to be 20 moved by an intermediate tool such as a hook or poker commonly employed.

I accomplish the above results by means of the device illustrated in the accompanying drawing which forms a part of this specification and in which:

25 Figure 1 is a front elevation of my improved draft regulator attached to a stove door only a sufficient portion of the latter being illustrated to show the relation of the parts; Fig. 2 is a transverse section on the line 2—2 of Fig. 1; Fig. 3 is a longitudinal section on the line 30 3—3 of Fig. 1, and Fig. 4 is a detail, enlarged, of the slide retaining collar and post, some of the parts being in section.

Referring to the drawing in detail, the numeral 5 indicates a stove ash-pit door supplied with the usual 35 draft apertures 6 and furnished with a slide consisting of a plate 7 divided by transverse strengthening ribs 8, which are continuous with a marginal rib or flange 9, into a series of panels 10, the alternate panels being provided with openings 10^a. The said plate is furnished 40 with a horizontal slot 11 through which passes a post 12 firmly fixed in the door plate 5. The post carries a sleeve 13 which abuts against a head 14 formed on said post, and a conical collar 15, having a flange 16 through which the post passes. Between the flange 16 and the 45 sleeve 13 is placed a coiled compression spring 17 which surrounds the post and exerts constant pressure between the fixed abutment or sleeve 13 and its movable abutment, the flange 16 of the collar 15.

The margins of the apertures 6 in the door plate 5 50 are slightly raised by ribs 18, and these ribs are milled or otherwise finished to form a plane seat for the movable slide 7. In like manner the inner surface of said slide plate 7 is furnished with slightly projecting ribs

19, corresponding in location with the position of the ribs 18, and these ribs are likewise finished to form a 55 tight joint when in opposition with the aforesaid ribs 18 as shown in Figs. 2 and 3. It will be seen that the action of the spring 17 against the collar 15 will cause a certain amount of friction proportional to the strength of said spring and this friction will hold the slide at 60 whatever point it may be placed in its lateral movement.

To actuate the slide I provide a lever 20 pivoted to the door plate 5 above the slide, by a bolt 21. This lever passes downward over the slide and terminates 65 in a rounded end 22 which curves outwardly away from the face of the door and is furnished with an orifice 23. Near the middle portion of the lever 20 is located a lug 24 preferably formed integral with the slide 7 which engages a longitudinal slot 25 in the said lever 70 and when the latter is moved laterally it will slide the plate 7 in the same direction by means of this lug. The outer end of the post 12 is received in a transverse slot 26 in the lever 20 and serves as a stop to limit the lateral motion of said lever.

In order to prevent a rotation of the slide plate 7 on its central point 12 two lugs 27 are provided which are placed below the margin of the plate 7 and on either side of the median line, said lugs being preferably cast with the door plate.

It will be obvious that when the lever is thrown to the limit of its excursion toward the left the closed panels 10 of the slide will coincide with the apertures 6 in the door plate 5 and as the contiguous surfaces are finished, to give a tight fit no air can pass through the 85 draft openings. When the lever is thrown wholly or partially to the right, however, the apertures 10^a in the panels will register to a corresponding extent with the draft openings 6 and the action of the spring 17 will preserve the adjustment until the lever is again actuated.

Having thus described my invention what I claim is:

In a draft regulating device, a fixed plate having draft openings therein and provided with a stud, a shutter slidably mounted on said fixed plate and provided with 95 draft openings, a horizontal slot and a stud, a lever pivotally mounted on the fixed plate and provided with a transverse slot receiving the stud on the fixed plate, and with a longitudinal slot fitting the stud on the shutter, and resilient means for holding the fixed plate and the 100 shutter in close frictional contact.

In testimony whereof I affix my signature in presence of two witnesses.

CHARLES M. GENTHNER.
